UNITED STATES PATENT OFFICE

EDWARD E. GOLD, OF NEW YORK, N. Y., ASSIGNOR TO GOLD CAR HEATING & LIGHTING COMPANY, OF BROOKLYN, NEW YORK, A CORPORATION OF NEW YORK

TRAIN PIPE CONNECTION

Application filed July 10, 1928. Serial No. 291,648.

This invention relates to improvements in train pipe connections used as a means whereby the pipes of the various cars of a railway train may be readily coupled and uncoupled. In the early history of the construction of railway rolling stock, train units were of relatively small dimensions and train pipes were of proportionately small diameter. The end sections of such train pipes consist of straight lengths of rubber tubing to the ends of which the pipe couplings were connected. End sections so formed could be readily bent by hand to a sufficient degree to effect a coupling without the aid of tools. As the size of train units increased, it became necessary to use train pipes of larger and larger diameters, as a result of which the flexible tubing used in the end sections had to be correspondingly increased in diameter. A stage was finally reached in this development at which the tubing which would have been required would have been so stiff and inflexible as to render it practically impossible to bend it from its rectilinear form to the degree of curvature necessary to effect a coupling without the aid of tools. The use of flexible tubing as end sections for train pipes of large diameters was, therefore, abandoned altogether, and for a number of years large sums of money have been appropriated to experiments in an attempt to use metal end sections made sufficiently flexible to effect a coupling by means of ball joints and swivel joints of various types. Such articulated metal end sections are not only relatively expensive as compared with simple flexible tubing, but have not been found to be altogether satisfactory. It is, therefore, an object of the present invention to provide an end section of flexible tubing of dimensions and material such that, if made in rectilinear form, it could not be readily flexed by hand to a sufficient degree of curvature to effect a coupling, said section having a normal curvature so closely approximating that of a coupled section that it may be readily flexed to the extent necessary to effect a coupling without the aid of tools.

In the drawings illustrating the preferred form of the invention,—

Figure 1 is a side view of a piece of heavy flexible tubing adapted for use as an end section of a train pipe, a part of said piece of tubing being indicated as having been cut away to reveal its internal structure. 55

Fig. 2 is a cross-section through the piece of tubing illustrated in Fig. 1, the section being taken along the line 2—2 thereof and viewed in the direction indicated by the arrows. 60

Fig. 3 is a side view of a pair of train pipe end sections including elements of curved flexible tubing embodying the invention, the sections being indicated in the relative positions which they assume when the ends of the cars, on which they are used, are brought to the positions in which the sections are intended to be coupled. 65

Fig. 4 represents the same pair of end sections after the coupling has been effected. 70

Referring first to Fig. 3, each end section comprises a short length of curved flexible tubing 20, having a nipple 21 inserted in each end thereof and securely held in place by a clamp 22. Each end section 20 is secured to the end of a train pipe 23 by suitable fittings, such, for example, as the elbow 24 and threaded coupling 25. To provide for the coupling of the end sections they have at their lower ends pipe couplings 26 of any suitable character, such, for example, as the coupling illustrated in the Kitchen Patent No. 1,056,184, of March 18, 1913. Pipe couplings of this general type are well known in the prior art and need not be described in detail. 80

If desired, each of the end sections may be supported by means of a chain 27 having one end connected with an eye 28 provided for such purpose on the coupling and the other end connected with any fixed part of the car structure (not shown). 85

It should be kept in mind, in viewing the train sections as illustrated in Fig. 3, that the curvature of the tubular elements 20 is that in which they are moulded and cured and not a curvature resulting from stress applied to the end sections by the supporting chains 27. 95

It will be apparent from a comparison of Figs. 3 and 4 that the coupling elements 26 may be coupled by merely raising the ends 100

and permitting them to drop into place as illustrated in Fig. 4, such operation requiring but a slight additional bending of the curved tube sections 20.

6 This is clearly indicated in Fig. 3 in which the broken lines 20' represent the curvature of the end sections when the couplings have been raised to positions from which they may be dropped into their coupled relation and the broken lines 20" represent the curvature of the coupled sections.

10 In Fig. 1 is illustrated one of the tubular end sections, which may be constructed of any suitable plastic material having the properties of rubber composition. Such tubular section may be built up of various layers of material herein indicated as comprising three layers 29, 30 and 31, reinforced with asbestos fabric or other fibrous material, the whole structure being moulded to the desired curved form and vulcanized or otherwise cured so as to approximate, when completed, the curvature of a coupled end section.

15 The particular form and degree of curvature of the tubular section is a matter of secondary significance. It is important, however, that the curvature approximate that of a coupled section sufficiently to enable a train-hand, without the aid of tools, to effect a coupling of a pair of end sections made of flexible tubing of such dimensions and stiffness that such coupling could not be readily effected if the end sections were made of ordinary straight tubing. This reduction of the degree 20 of bending of the end section necessary to effect a coupling materially reduces the distortion of the wall structure of the tubing of which it is made at each coupling operation, thus greatly increasing its period of usefulness, thereby effecting a corresponding economy 25 of labor, material and service.

30 End sections made in accordance with this invention are relatively simple in construction as compared with articulated metal end sections and have been found as a result of experiment to be more economical and satisfactory than the more complicated and elaborate constructions which they are designed to replace.

35 40 45 50 55 60 65 70 75 80 85 90 95 100 105 110 115 120 125 130 135

The invention is not intended to be limited to the preferred form herein selected for purposes of illustration but should be regarded as including modifications and variations thereof within the scope of the appended claim.

What is claimed is:

A pair of end coupling sections for a train pipe comprising tubes of flexible material having the physical properties of a composition of rubber and fibrous material, each provided at one end with means for connection with a train pipe section and at the other end with a coupling head, said heads being complementary and adapted to be connected by a rotational movement of each with respect to

the other about parallel horizontal axes, and each of said tubes being of such physical properties and dimensions that it could not be readily flexed from rectilinear form to the degree of curvature necessary to effect a coupling with a complementary section without the aid of tools, each tube having a normal curvature so closely approximating the ogee form of a coupled section that it may be readily flexed by hand to the extent required to impart to its coupling head the rotational movement necessary to effect a coupling.

In witness whereof, I have hereunto signed my name.

EDWARD E. GOLD. 80
